H. SCHRADER,
SANITARY CAN,
APPLICATION FILED JAN. 27, 1920.

Patented Nov. 8, 1921.

UNITED STATES PATENT OFFICE.

HERBERT SCHRADER, OF WHEELING, WEST VIRGINIA.

SANITARY CAN.

1,396,065.

Specification of Letters Patent. Patented Nov. 8, 1921.

Application filed January 27, 1920. Serial No. 354,423.

To all whom it may concern:

Be it known that I, HERBERT SCHRADER, a citizen of the United States of America, and resident of Wheeling, county of Ohio, and 5 State of West Virginia, have invented certain new and useful Improvements in Sanitary Cans, of which the following is a specification.

This invention relates broadly to metallic 10 cans of the so-called sanitary type, and more particularly to a head and closure for such cans.

The primary object of the invention is to provide a can of the general character used 15 for the preservation of food products, which, following use as a preserving container of any of the various liquid or non-liquid products of the cannery or packing house, is adapted for re-use in the domestic preserva- 20 tion of fruits, vegetables and like products.

The cans heretofore employed by canners and packers have uniformly possessed forms which precluded their re-use as containers for products which require that they be hermetically sealed. Where used by canners of 25 food products, such as fruits and vegetables, either the closure has been fitted to hermetically seal the can in such a way that access for removal of the contents of the 30 latter could be had only by destroying or mutilating the can to the extent that its re-use as a preserving container is rendered im-possible or impracticable, or, where the closure has been removed without mutilation, its 35 form is such that its re-application to pro-duce a hermetically tight joint is imprac-ticible under conditions which obtain in the ordinary household. Further, the cans hereto-fore used by packers of non-liquid prod-40 ucts, as lard, coffee, and the like, have ordi-narily had removable heads or caps of forms not adapted for hermetic sealing.

The object of the present invention is to provide a can which may be originally em-45 ployed by the canner or packer to hermeti-cally seal his product, which may be readily opened without mutilation of, or injury to, either the can or the closure, and which, when empty, may be re-used by the housewife in 50 the manner of ordinary commercial forms of preserving cans for the packing of foods which require that they be hermetically sealed.

A further object is to produce a can and 55 closure of the character mentioned which is simple in its construction and which can be

manufactured at a cost little, if any, in ex-cess of that of producing the cans used here-tofore, as aforesaid, and which, therefore, provides for a substantial economy being ef-fected when re-used by the housewife for 60 preserving purposes.

With these and other important objects in view, the invention resides in the features of construction which will hereinafter be 65 described, reference being had to the accom-panying drawings, in which—

Figure 1 is a central section, greatly en-larged, of the can head and the removable 70 cap or cover as said parts appear prior to ap-plication of said cap or cover, and—

Fig. 2 is a similar section of the upper end 75 of a can, showing the positions occupied by the parts when the cap or cover has been applied for closing the can.

Referring to said drawings, 1 indicates the body of a can to the upper end of which is attached, as by double seaming or by solder-ing, the circumferential downturned flange 2 of a head which is generally designated by 80 the numeral 3. Said head is pressed from sheet metal to form an inwardly and down-wardly inclined circular portion 4 which has said flange 2 formed peripherally thereof, an inwardly and upwardly inclined portion 5, 85 and a substantially vertical neck portion 6. Said inclined portion 5 is joined to the in-clined portion 4 by a short vertical wall 7 which constitutes an inwardly facing shoul-der, and said neck portion 6 rises from the 90 inner edge of said portion 5.

An outwardly turned roll or bead 8 is formed at the upper edge of the neck por-tion 6, the same being designed to receive in 95 seated relation thereto the roll portion 9 of a cap or cover 10. Said roll portion, which provides a downwardly facing channel for the reception of said bead 8, is formed at the upper terminus of a substantially ver-tical wall 11 located peripherally with re-spect to the flat central portion 10* of said 100 cap or cover; and said channel is adapted to have a suitable sealing material 12, as a rubber cement or other compound, disposed therein to form with said bead 8 a tight her-105 metic seal.

The vertical wall 11 of the cap or cover 10 is adapted to fit more or less snugly the interior of the neck portion 6 to form a her-metic sanitary closure. Following applica-110 tion of said cap or cover, as at the cannery or packing house, downwardly directed pres-

sure is applied, as by means of a press, not only for firmly seating said cover to a point where the bead 8 is embedded in the sealing cement, but also to depress the inwardly and 5 upwardly inclined portion 5 of the head 3 to the horizontal plane, as shown in Fig. 2.

As is obvious, the diameter of the mouth opening defined by the neck 6 is materially reduced by the downward bending of the inclined portion 5 to a horizontal plane, as 10 described, said neck being contracted to the extent that it very closely embraces the wall 11 of the cover, resulting in the formation of an especially effective seal.

15 The outer wall 13 of the roll 9 of the cap 10 is of such length that, when said cap is seated in can-sealing position, its lower edge remains elevated above the surface of the portion 5 of the head 3 to the extent that the 20 edge of a suitable instrument may be introduced beneath said edge for prying off the cap. To further facilitate the introduction of such instrument, the said edge may be flared outward slightly, as shown at 14.

25 When the can is re-used for domestic canning or packing, the cap is forced into closing relation to the mouth opening, after which a sealing cement or wax may be flowed into the channel between the shoulder 30 7 and the neck 6 to embed the lower or flared edge 14. Obviously, the can constructed as

described is adapted for such domestic sealing equally as well as the common forms of cans heretofore designed and commercially available for household canning or preserving of fruits, vegetables and the like. 35

What is claimed is—

In a can, a body having a head formed with an inclined part which extends downwardly from the top of the body, the lower 40 end of the inclined part being extended downwardly and then substantially parallel to the plane of the top of the body and then upwardly to form a relatively shallow channel, and a cap having a downwardly facing 45 channel receiving the upwardly extending part of the head and having the lower edge of the outer wall defining the channel flared outwardly to overlie the bottom of the channel of the head in spaced relation thereto and 50 in spaced relation to the lower terminal of the inclined part so as to allow an instrument to be engaged with the inclined part of the head and with the flared part of the cap so as to enable removal of the latter. 55

In testimony whereof I affix my signature in presence of two subscribing witnesses.

HERBERT SCHRADER.
